(57) **CLAIM**

The ornamental design for a case for portable electronic communications device, as shown and described.

DESCRIPTION

FIG. 1 shows a perspective view of a first embodiment of a design for a case for portable electronic communications device.

FIG. 2 shows a front view of the first embodiment.

FIG. 3 shows a back view of the first embodiment.

FIG. 4 shows a left-side view of the first embodiment.

FIG. 5 shows a right-side view of the first embodiment.

FIG. 6 shows a top view of the first embodiment.

FIG. 7 shows a bottom view of the first embodiment.

FIG. 8 shows a perspective view of a second embodiment of a design for a case for portable electronic communications device.

FIG. 9 shows a front view of the second embodiment.

FIG. 10 shows a back view of the second embodiment.

FIG. 11 shows a left-side view of the second embodiment.

FIG. 12 shows a right-side view of the second embodiment.

FIG. 13 shows a top view of the second embodiment; and,

FIG. 14 shows a bottom view of the second embodiment.

The grey tone in the figures is surface shading that indicates claimed subject matter. The broken lines immediately adjacent the shaded surfaces represent boundaries of the claimed design. All other broken lines depict unclaimed environment. The broken lines and unshaded surfaces form no part of the claimed design.
